UNITED STATES PATENT OFFICE.

RONEY P. TOMPKINS, OF MOUNT VERNON, NEW YORK.

INK-WELL.

1,120,170.

Specification of Letters Patent. Patented Dec. 8, 1914.

Application filed November 15, 1913. Serial No. 801,121.

To all whom it may concern:

Be it known that I, RONEY P. TOMPKINS, a citizen of the United States of America, and residing at Mount Vernon, in the county of Westchester and State of New York, have invented certain new and useful improvements in Ink-Wells, of which the following is a specification, such as will enable those skilled in the art to which it applies to make and use the same.

This invention relates to ink-wells, and the main object thereof is to provide such a device in which the reservoir is the bottle in which the ink has been vended, thus avoiding the present necessity for filling reservoirs from the bottles, with a consequent saving of time, trouble, and frequently annoyance, and also avoiding the possibility of spilling and wasting ink in such transfer.

A further object is to provide an ink-well wherein the ink at the dip is always maintained at the same height automatically, irrespective of the size of the reservoir or bottle.

A further object is to maintain an original bottle in substantially sealed condition whereby the ink remains in its original condition until entirely used.

A further object is to so connect the bottle with the well as to preclude the possibility of contamination by dust, dirt, and the like which gathers at the necks of bottles from which ink-well reservoirs are filled at present.

A further object is to so construct the well as to positively prevent spilling ink in the event of the well being upset accidentally or tilted intentionally; and further objects are to provide such wells which maintain an ample supply of ink in a readily accessible position, which are thoroughly practical and may be made very ornamental, and which are comparatively inexpensive.

My invention is fully set forth in the following specification, of which the accompanying drawings form a part, in which the separate parts are designated by the same reference characters in each of the views, and in which:

Figure 1 is a vertical, longitudinal, section taken centrally through an ink-well constructed in accordance with my invention; Fig. 2 is a section taken on the line 2-2 of Fig. 1; Fig. 3 is a fragmentary detail showing a result; Fig. 4 is an enlarged view of a bottle puncturing pin which I employ;

Fig. 5 is a section taken on the line 5-5 of Fig. 4; Fig. 6 is an end view of the head of said pin; and Fig. 7 is a top view of the cap which I provide for the bottles to be used with my ink-well.

In the drawings forming a part of this application I have shown a present preferred form of my ink-well, comprising a base *a* having an inverted bell-shaped member *b* thereon and a circular member *c* provided with a screw-threaded recess *c*² at the bottom of which is a spiral groove *a*² terminating in a circular recess *a*³ at its inner end and at its outer end in a longitudinally arranged groove *a*⁴ in turn terminating in the dip-well *a*⁵ beneath the central opening *o*² of the bell *b* through which the pen is passed for inking. The screw-thread of the recess *c*² is adapted to engage the threaded cap *d* of a bottle *d*², said cap being perforated, preferably centrally, as shown at *d*³ and being provided with the usual cork or other washer *d*⁴ therein but this washer is not punctured when the bottle is filled or offered for sale, and, as shown, I may provide a recess *d*⁵ at the bottom of the bottle for use as a receptacle for pins, paper clips, a sponge, or the like, and I may also corrugate or dentate the edge of this receptacle, as shown at *d*⁶ to serve as a pen holder.

Seated in the recess *a*³ is a pin *e* which is grooved longitudinally, as shown at *e*² and slotted at the lower end to form spring tines *e*³ to frictionally engage the wall of said recess, said lower end being enlarged to form a shoulder *e*⁴ which is flush with the floor of the recess *c*² and I provide a washer *e*⁵ which rests against said shoulder and upon the floor of the recess *c*² and is of substantially the same diameter as said recess, and it will be noted that the recess *a*³ is of much greater depth than that of the spiral groove, said groove, as well as the groove *a*⁴ having an inclined floor leading toward the dip-well *a*⁵, this being clearly shown in Fig. 2, and the reason for which will be later explained.

In practice, the filled bottle *d*², just as purchased, is inverted and the pin *e* forced through the perforation *d*³ of the bottle cap and through the washer *d*⁴ therein and into the bottle and, when the screw-thread of the bottle cap is engaged by the thread of the recess *c*², the bottle is rotated to screw the bottle cap into said recess until the cap bears upon the washer *e*⁵ and an air-tight

and dust-proof connection results between the bottle and the base *a*, with the pin within the bottle and the ink free to flow through the groove *e*² to the spiral groove *a*² and thence to the dip-well, care being taken to have the groove *e*² register with the inner end of the spiral groove *a*², as clearly shown in Figs. 2 and 3. In this flow of ink air passes to the bottle to replace the ink being removed until the ink reaches a level equal to the lower surface of the wall dividing the members *b* and *c* at which time no air may pass to the bottle because of the air-seal thus formed, and the flow of ink ceases but as soon as this ink level is lowered, through use of evaporation, air again enters the bottle until this level is again attained, and an automatic ink supply results in the degree of use or evaporation and the ink in the dip-well is maintained at a fixed level at all times. If the ink-well should be upset the ink in the dip-well is prevented from escaping therefrom because of the interior capacity of the bell *b* and no ink may escape from the bottle because of the air-lock formed by the spiral groove *a*², this air-lock being clearly shown in Fig. 3, and my ink-well is, therefore, immune from ink spilling under all conditions, and it is in order to positively insure such immunity that I form the spiral groove *a*² of relatively slight depth for it will be observed, by reference to the broken line in Fig. 1, that if the ink-well be tilted on its dip-well end, the level of ink does not reach a point below the under side of the wall between the members *b* and *c* and the air-seal at this point is maintained and no air may enter the bottle. If the spiral groove were of a depth equal to that of the dip-well the ink level in the said spiral groove would be lowered in such tilting and would destroy the air-seal referred to and admit air to the bottle and allow the ink in the bell to overflow because the ink level at such moment of overflow would be that of a line drawn from the bottom of the spiral groove through the orifice *b*² and which line would be beneath the wall between the members *b* and *c* and the bottle would be emptied and the ink flow from the ink-well, but this is overcome by decreasing the spiral groove depth to maintain the air-seal.

While I have shown one form of con-

struction I do not limit myself thereto, either as to the well construction, the means for bottle connection therewith, or as to the formation of the puncturing pin *e*, as many changes in and modifications thereof may be made without departing from the spirit of my invention or sacrificing its advantages, my invention, as hereinafter claimed, consisting primarily of an ink-well having means permitting the use of an ink-bottle as purchased as the ink reservoir, as also of a bottle formed to permit such use, and means for preventing the spilling of ink should the well be upset in connection with the maintenance, automatically, of a fixed ink level.

With such reservations to myself, what I claim as new, and desire to secure by Letters Patent, is:—

1. An ink-well, comprising a base provided with a screw-threaded recess having a horizontal bottom and a groove formed beneath said recess and in said bottom, and having a portion thereof on each side of the central, vertical, plane of the ink-well, said base having a dip-well and a groove connecting the same with said first named groove, a reservoir detachably mounted in said recess, and a channeled pin projected into said reservoir and the channel of which connects with the inner end of said first named groove.

2. An ink-well, comprising a base provided with a screw-threaded recess having a horizontal bottom having a spirally formed groove therein and beneath the same, a portion of said spiral groove being arranged on each side of the central, vertical, plane of said ink-well, said base having a dip-well and a groove connected with said first named groove, a reservoir detachably mounted in said recess, and a channeled pin projected into said reservoir, the channel whereof connects with the inner end of said spiral.

In testimony that I claim the foregoing as my invention I have signed my name in presence of the subscribing witnesses this eleventh day of November 1913.

RONEY P. TOMPKINS.
